Attest:

UNITED STATES PATENT OFFICE.

LEWIS A. BROWN, OF ST. LOUIS, MISSOURI.

DESIGN FOR A BADGE.

SPECIFICATION forming part of Design No. 25,553, dated June 2, 1896.

Application filed March 30, 1896. Serial No. 585,493. Term of patent 31 years.

To all whom it may concern:

Be it known that I, LEWIS A. BROWN, of the city of St. Louis, State of Missouri, have invented a new and original Design for a badge, of which the following is a full, clear, and exact description, reference being had to the accompanying drawings, forming a part hereof.

In the drawings, Figure 1 is a front elevation of a badge embodying my design. Fig. 2 is a horizontal sectional view taken approximately on the indicated line 2 2 of Fig. 1.

The leading feature of my design consists of a circular body or disk, on the front face of which appears a raised marginal border, and in the center of the face of which disk or circular body there appears a smaller circular body, the same being concentric with the circumference of the first-mentioned disk or body, which smaller body has a raised marginal border.

1 indicates the circular body or disk, upon the front face of which appears the raised marginal border 2. Extending forward from the center of the face of the body 1 is the cir-

cular body 3, being of a size much smaller and arranged concentric with the circumference of the disk or body 1. The outer face of this smaller body 3 projects into a plane beyond that occupied by the face of the body 1, and the face of said smaller body 3 is provided with a raised marginal border 4. The face of this smaller body 3 within the border 4 and the face of the disk or body 1 between the body 3 and the raised marginal border 2 are smooth and plain, in order that suitable marking may be made to appear thereon.

When viewed in front elevation, the design presents the appearance of a bordered disk, on the face of which appears a smaller bordered disk.

I claim—

The design for a badge, as herein shown and described.

In testimony whereof I affix my signature in presence of two witnesses.

LEWIS A. BROWN.

Witnesses:

S. G. WELLS,
MAUD GRIFFIN.
